(57) **CLAIM**

The ornamental design for a clock and watch face, as shown and described.

DESCRIPTION

FIG. 1 is a front perspective view of a watch and clock face; FIG. 2 is a front view thereof; FIG. 3 is a top plan view thereof; FIG. 4 is a bottom plan view thereof; FIG. 5 is a left side view thereof; and, FIG. 6 is a right side view thereof.

The broken lines in the drawings are used to show portions of the watch and clock face that do not form part of the claimed design.
